WARP-STOP MOTION

Harry W. Thatcher and Carl D. Brown, Honesdale,
Mass., assignors to Draper Corporation, Hone-
dale, Mass., a corporation of Maine.

Application November 8, 1947, Serial No. 784,790.

9 Claims. (Cl. 139—358.)

1

This invention relates to stop motions for looms, and more particularly to warp stop motions of the type employing a plurality of spaced banks of drop wires each of which is supported by an individual warp thread and is employed to initiate loom stopping action when it is allowed to fall incident to breakage or excessive slackening of its associated warp thread.

Stop motions of the type toward which the present invention is directed are conventionally provided with supporting structures, one at each loom side, which support detector bars and separator bars extending generally between the loom sides. The separator bars serve the dual function of separating the individual drop wire banks and supporting the sheet of warp threads and its load of drop wires. A typical stop motion provides for each warp thread an individual drop wire, which straddles or has passed through a slot therein a detector bar and which is supported by its respective warp thread. The drop wires are because of space requirements divided into a plurality of groups or banks and each drop wire is individually loosely guided between two separator bars to keep drop wires of one bank from interfering with those of other banks. The separator bars support the warp thread which holds up the individual drop wire, in a position in which the upper end of the detector bar slot clears the upper edge of the detector bar sufficiently to permit a certain degree of slackness in the thread, to prevent warp stop action if a warp thread becomes merely slightly slack or loose. If however, this degree of slackness is exceeded or if the warp thread breaks, the drop wire is by action of gravity and loom vibration lowered to a position where it engages the detector bar and initiates loom stoppage. Detector bars are of various sorts and are of both electrical and mechanical types. The present invention is illustrated in connection with a stop motion employing electrical detector bars, but as will become evident hereinafter, certain features of the invention are equally applicable to stop motions of the mechanical type.

Under certain circumstances encountered in weaving mills it is desirable that those members of the warp stop motion which extend across the loom, such as the detector bars and separator bars, be readily removable from the loom. For example, upon exhaustion of the warp supply on the warp beam of the loom, it is common practice to remove with the woven cloth and trailing warp ends the harness frames and drop wire banks, to allow of immediate replacement of the

2

old warp beam by a new warp beam whose warp has already been drawn into a set of drop wires and harness frames. The new or replacement warp beam has its warp threads threaded through replacement harness frame heddles and drop wires so that the shut-down time or idle period of the loom can be made as small as practicable. The replacement harness frames and drop wire banks are tied to the new warp beam, the banks of wires being mounted on dummy detector bars, and as soon as the old warp beam, drop wire banks and harnesses are out of the way the new beam is fitted into the loom. Fitting of the beam is followed by hanging of the replacement harnesses and replacement of the dummy bars by the detector bars. It sometimes is the practice to lift out the old set of detector bars of the warp stop motion with the old warp ends, especially when the drop wires are threaded on the detector bars, but leaving the separator bars in place across the loom. This necessitates lifting the replacement set of harness frames over the separator bars, and since the frames are quite heavy, creates an arduous task. Thus it is seen to be desirable to be able to readily remove the detector bars so they may be taken with the old warp, and to be able to readily remove the separator bars as well, so the harness frames need not be lifted as mentioned, but may be moved forwardly through the space normally occupied by the mentioned bars, assuming the warp stop motion support brackets are sufficiently far apart to provide clear passage space for the harness frames.

It is of considerable importance in both mechanical and electrical types of warp stop motions employing detector bars that the detector bars be maintained each securely in a fixed position, to avoid vibration-induced false indications of warp thread breakage. Also it is of great importance in electrical stop motions of the type mentioned to provide good electrical contact with each of the electrodes of each detector bar, to insure that a fallen drop wire will in all cases be effective to promptly initiate loom stoppage. Heretofore difficulty has been met in preventing the detector bars from shifting their positions, and in maintaining effective electrical contacts at all of the electrodes of the detector bars. The supporting brackets located at the sides of the loom have heretofore been of cast construction providing cast wells or recesses for seating the separator bars and detector bars, and it has been found that irregularities in size and shape of the wells are a source of much of the objection-

able looseness and misalignment of parts. One attempt to avoid these difficulties resulted in a supporting structure composed of a rod on which were mounted a number of specially machined blocks. It has been found however, that the numerous machining operations necessary make that structure too expensive for practical purposes. Furthermore, unless both the support blocks and the bars supported thereby are very accurately machined, one or more of the bars soon is loosened in loom operation, with the aforementioned undesirable results. Additionally the multiple-block type detector bar support structure utilized either a single-piece electrical conductor in the form of a spring, or a series of conductors bolted together, to interconnect the live electrodes of the detector bars. The single-piece type of connector is found to give unsatisfactory and non-uniform contact; while the bolted-together conductors, although furnishing excellent electrical connections, are bothersome to disassemble and reassemble each time the detector bars are removed and replaced in operation.

With the above considerations in view it is an object of the invention to provide a warp stop motion including support means so constructed and arranged as to provide clear forward passage space for movement of the harness frames therebetween and providing for ready release and removal of the separator bars and detector bars from the support means. It is another object of the invention to provide an electrical warp stop motion having detector bars having live and grounded electrodes, and including a base an readily removable unitary means acting to positively electrically interconnect the live electrodes of the detector bars and to firmly maintain the detector bars in fixed position relative to the base. Another object of the invention is to provide a warp stop motion the several parts of which are so made that the recesses or seats for the detector and separator bars, and other interfitting surfaces, may easily and economically be machined to provide accurate spacing and seating of the parts while maintaining ease of assembly and disassembly of the bars. Another object is to provide general improvements in warp stop motions for looms.

The foregoing objects and others that will hereinafter become evident from a consideration of the whole of this disclosure and the environment thereof are attained by the present invention, a preferred embodiment of which is disclosed in the following description considered with the accompanying drawing forming part of the disclosure.

In the drawings:

Fig. 1 is a top view of a warp stop motion according to the invention, with portions of the separator bars and detector bars removed to improve the scale of the figure;

Fig. 2 is a sectional view taken substantially along lines 2—2 of Fig. 1 in the direction indicated;

Fig. 3 is a sectional view taken substantially along planes indicated by lines 3—3 of Fig. 2, in the direction there indicated;

Fig. 4 is a partial sectional view of supporting structure and appurtenant parts at one side of the loom, taken along planes indicated by lines 4—4 of Fig. 2 and viewed in the direction there indicated;

Fig. 5 is a view in elevation of a stop motion base adapted to be mounted on conventional

warp stop motion brackets and to support other principal components of the stop motion at one side of the loom;

Fig. 6 is a sectional view taken along line 6—6 of Fig. 5 and in the direction indicated;

Fig. 7 is a plan view of a part of the warp stop motion;

Fig. 8 is a view in elevation of a part of the warp stop motion;

Fig. 9 is an end view of structure depicted in Fig. 8;

Fig. 10 is a sectional view taken along a plane indicated by lines 10—10 of Fig. 8, viewed in the direction indicated;

Fig. 11 is a plan view of a component of the warp stop motion; and

Fig. 12 is a sectional view taken along a plane indicated by line 12—12 of Fig. 11 and in the direction indicated.

Referring to the drawings, and more specifically to Figs. 1 and 2, the stop motion includes two principal supporting structures, one at each side of the loom and respectively designated generally by numerals 8 and 9. These supporting structures include a pair of bracket supports 10, 11 of any suitable shape arranged to be secured to respective loomsides and upon which the warp stop motion proper is supported. Bracket supports 10, 11 have secured thereto respective support brackets 12, 13 as by respective bolts 14, 15, the brackets being alike in form.

These brackets, 12 and 13, serve as elements upon which the warp stop motion base members may be supported and adjustably rocked to bring the various warp stop motion parts into proper angular relationship with the warp threads. To allow such rocking adjustment to be effected brackets 12, 13 are provided with arcuate holes 16, 17 (see Fig. 2) through which bolts 18 and 19 are adapted to pass. Bracket supports 10, 11 and brackets 12, 13 are or may be of conventional form and per se are not of the present invention.

In view of the general similarity of the warp stop motion structures at the respective loomsides, the following description will for the sake of brevity be limited insofar as is practicable to the structure at one side of the loom; and only in those cases wherein the parts at opposite sides of the loom are materially different will both be described or the differences noted.

Held to bracket 12 by the aforementioned bolts 18, 19 is a base 20 (see Figs. 2 and 5) which has an integral downwardly extending flange 21 provided with arcuate holes 22, 23 arranged to register with holes 16, 17, respectively, in bracket 12. It will be evident, therefore, that base 20 may be angularly adjusted through a considerable range of positions with respect to the warp threads. Secured in base 20 at opposite ends thereof are upright studs 24, 25 upon which are mounted in superposed fashion other members of the warp stop motion structure as will presently be described. Also secured to base 20 as by means of cap screws 26, 27 turned into tapped holes 28, 29 formed in the base, are clamp members 30, 31 (see Fig. 2). These clamp members are interchangeable and are formed and arranged to support and clamp warp guide rods 32, 33 which extend across the loom. Rod 32 is formed of stock of rectangular cross-section, and rod 33 is formed of stock of round (preferably tubular) cross section. By employment of two clamp members 30 two warp support rods 32 may be employed; and likewise if two clamp members 31 are used, warp support rods like 33 may be

employed. Interchangeable clamps are desirable so warps of various widths, weights, and other characteristics may be accommodated. The clamp members and associated rods are so formed with respect to shape and size that regardless of the combination of rods 32, 33 employed, the level of the warp sheet will be the same, it being understood that a clamp member 31 will always be used with a round rod and a clamp member 30 with a rectangular rod. Base 20 is of the form and shape illustrated, at one side of the loom; and its mate at the opposite side of the loom is of complementary form of opposite hand. The base has an inwardly directed ledge 34 (see Fig. 6) which is provided with vertical, milled slots 35 (Fig. 5) which are formed of such width as to accommodate the ends of respective drop wire bank separator bars 36 as indicated in Fig. 2. To support bars 36 in slots 35 a detachable, shaped member 37 is fastened to the under side of the base, as by means of screws 38, 39, in position to underlie the ends of the separator bars, as indicated in Fig. 2. The milled slots are readily formed in a single machining operation, and allow ready upward removal of the separator bars from base 20. The proportions of member 37 and bars 36 are such that the top surfaces of the bars will be aligned with the uppermost surfaces of rods 32, 33 when member 37 is in place.

Supported on seats 24a, 25a formed on studs 24, 25, respectively, is a detector bar support 40 (see Fig. 7), provided with bored ears 41, 42 at its opposite ends and adapted for placement upon and positioning by, studs 24, 25, as indicated in Fig. 2. As shown in Fig. 7, detector bar support 40 is provided with a series of milled transverse horizontal slots 43, which are of such width and depth as to accommodate respective ends of detector bars 44. (See Figs. 2, 3 and 4.) Support 40 is also provided with a series of vertically extending channels 45 which are of such depth and disposition as to allow ready upward movement therethrough of the respective ends of separator bars 36. It is evident that slots 43 may readily and accurately be cut in support 40; hence the detector bars may be accurately positioned in spaced-apart relationship. To prevent endwise movement of the detector bars out of slots 43 and for other reasons set out herein-after, a cap structure including a cap and a cap base is provided. The cap base, 46, has offset bored ears at its respective ends, the bores being so disposed and formed as to allow the cap base to be fitted onto studs 24, 25 above support 40 (see Figs. 1 and 2), in which position it is adapted to be held by nuts on the studs, as indicated. Cap base 46 is provided with laterally disposed pins 48, 49 (see Figs. 2 and 4) on which are fitted swivel screws 50, 51, each carrying a wing nut. The cap structure also includes a cap 52 arranged to be supported on pins 48, 49 of the cap base and held securely thereon by the mentioned swivel screws and wing nuts, the cap having suitable vertical slots 53 at its ends to accommodate the swivel screws. The swivel screws and wing nuts form quick-disconnect means attaching the cap to the cap base. Each swivel screw may, with its nut loosened, be rotated into or out of one of the vertical slots in the cap, as is evident from Figs. 1 and 2. Cap 52 is provided with a skirt 54 (see Fig. 3) which extends downwardly far enough to act as a stop to prevent endwise movement of detector bars 44 out of their slots 43. A second function of cap 52 is to

support means for firmly pressing the detector bars into firm seating relationship in slots 43, whereby detector bar vibration and creep are prevented, wear reduced or eliminated, and, in the case of electrical detector bars, the live upper electrodes are interconnected and the lower ground electrodes thereof are firmly grounded to the loom frame.

To achieve the desirable results just mentioned, and others to be mentioned later, cap 52 (see Figs. 2 and 3) has secured thereto in any suitable manner, as by screw means 55, passing through holes formed in the cap, a block 56 of electrical insulation employed to support a series of articulated electrically conductive pressure units. Block 56 is provided with a series of spaced-apart vertically disposed counterbored holes 57 through each of which is passed a respective headed pin 58. One head of each pin bears upon a respective washer 58a fitted in the counterbore of its hole. Loosely carried on each pin is an electrically conductive plate 59 (see Figs. 11 and 12), which has a centrally located flared aperture 59a through which the pin passes and into the flared recess of which aperture the headed or upset lower end of the pin may fit. Also carried by each pin is an electrically conductive spring 60 and a washer 61 disposed between the spring and the respective plate 59. Each spring 60 is applied on its respective pin in a compressed state, after which the washer 61 and plate 59 are applied and the pin upset, so when the spring is released it tends to press the plate against the upset end of the pin, as is evident from a consideration of Fig. 2. The pin, plate, spring and washers form one of a series of articulated electrically conductive pressure units each of which serves to maintain, in conjunction with another or other such units, a pair of detector bars fixedly seated in their respective slots 43, and further serves to effectively electrically connect the live (upper) electrode of an associated detector bar with an electrical bus bar 62 formed of a flat conducting strip through which pins 58 pass, and with others of the series of units, and to effectively ground the lower electrode of the associated detector bar to the loom frame via support 40. (See Fig. 2.) As depicted in that figure, alternate ones of the series of plates 59 straddle and thus electrically interconnect a respective pair of live detector bar electrodes, while the intervening plates straddle a respective pair of ends of the alternate plates. If desired, the plates may be deformed by stamping to form tits 59b and complementary depressions, as indicated in Figs. 11 and 12, the shapes and dispositions of the tits being such that a tit on one end of an alternate plate engages in a depression on an adjacent end of an intervening plate or vice-versa. The tits and depressions aid in maintaining the plates in proper relative positions and articulation of the plates under the action of springs 60. Thus it is evident that with cap 52 in place with the wing nuts tightened and the springs compressively urging plates 59 downwardly, the detector bars are firmly held seated in fixed positions in slots 43, that the live upper electrodes are effectively interconnected and to a bus bar, and that the lower ground electrodes are effectively grounded. It is evident that bus bar 62 may be employed as a live terminal and the loom frame or support 40 the ground terminal, of the electrical warp stop motion, these terminals being in turn connected in the conventional manner to the con-

ventional electric energy source and stop motion magnet.

Referring to Figs. 1, 2 and 3, it will be evident that the detector bars and separator bars may readily be removed from the support structure upon simply removing cap 52 (as by loosening the wing nuts on swivel screws 50, 51 and swinging the swivel screws outwardly from slots 53 and lifting the cap bodily from pins 48, 49); after which the bars are free for vertical movement unhindered by any part of the structure. The same action takes place at the opposite side of the loom, the only substantial difference being that the cap, 52', at that side is slightly different in form as will hereinafter be more fully explained. As indicated in Fig. 4, after cap 52 has been removed, which is a very simple operation, detector bars 44 may be lifted vertically from slots 43, and separator bars 36 lifted out of slots 35, the ends of those bars passing through respective channels 45 in detector bar support 40. Likewise, a replacement set of bars may readily be placed and locked in position in the supporting structures, and electrical interconnection of the sets of electrodes automatically effected upon replacement of cap 52. It will be understood that the articulated pressure units remain securely attached to cap 52 when the latter is removed, since block 56 is secured to the cap. Further it will be understood that when the cap is in place and the wing nuts on swivel screws 50, 51 are tightened, each of plates 59 will rise on its respective pin, hence slightly compressing its associated spring 60. It is thus that the springs are effective to cause complete seating of the detector bars and positive electrical interconnection of the sets of electrodes, live and grounded.

Since it is necessary electrically to interconnect one end only of the detector bars, the cap structure at the side opposite cap 52 may be somewhat simpler than cap 52. As indicated at the left hand side of Fig. 1, the live electrodes of the detector bars at that side are terminated some distance from the ends of the outer, grounded electrodes. A cap 52', shaped as indicated in Figs. 8, 9 and 10 is provided, somewhat similar to cap 52 but having no insulating block. Cap 52' is merely a casting having counterbored holes to receive pins 58' and spring 60', the pins each having a plate 59' similar to or like plates 59 and a washer 61' like washers 61 and being headed over at their top ends so as to be unable to escape from the cap. Cap 52' is mounted on pins exactly as is cap 52, but plates 59' do not press upon the live electrodes since the latter are terminated short of the cap as above noted. Rather, plates 59' press upon respective outer electrodes, holding the latter firmly seated in slots exactly as at their opposite ends. In other respects, the supporting structure at 9 is similar and complementary to that at 8.

It will be understood that in cases where the invention is applied to an arrestable vibrator or other mechanical type of warp stop motion, the cap structure at both sides of the loom may be that indicated at 59', since there are in that type of motion no electrodes to be maintained in electrical isolation from other structure.

When a new warp and harness frames are to be placed in the loom, screws 26, 27 and wing nuts on screws 50, 51 are loosened, at both sides of the loom. Guide rods such as 33, 34 and caps as 52, 52' are removed, and the detector and separator bars raised bodily from the loom. This

procedure requires only a few seconds time by an experienced person, and leaves the space between the respective bases 20 free for passage therebetween of the new harness frames. After hanging of the frames, replacement of the guide, separator, and detector bars is readily effected in an obvious fashion.

For clarity in the drawings we have omitted nearly all of the drop wires from the illustration. As is customary each detector bar is provided with its own individual bank of wires. The latter may be of any suitable conventional form, and per se are not of the present invention.

From a consideration of the above disclosure of a preferred embodiment of the invention it will be evident that while the objects of the invention are fully attained thereby, changes and modifications will occur to those skilled in the art. Accordingly we do not wish to be limited to the precise details of construction employed in the preferred embodiment, but what we claim is:

1. In combination in an electrical warp stop motion: a cap structure including a cap base, a cap, and quick-disconnect means attaching the cap to the cap base; said cap including a series of articulated electrically conductive pressure units and means insulating said units from the remainder of the cap structure, said units being normally self-interconnected electrically.

2. In a warp stop motion of the type having spaced banks of drop wires arranged on detector bars and means to support the detector bars, in combination therewith: a cap structure including a cap base, a cap, and quick-disconnect means attaching the cap to the cap base; said cap including a series of articulated pressure units each having a spring and arranged to collectively press the detector bars into fixed engagement with the support means.

3. In a warp stop motion of the type including spaced banks of drop wires, a detector bar for each drop wire bank, a separator bar for each space between next adjacent drop wire banks, support means at each end of the drop wire banks supporting adjacent respective ends of said detector bars and separator bars, and articulated pressure units positioned at at least one end of the drop wire banks and carried by and insulated from the support means for pressing each detector bar individually into firm contact with the support means.

4. In combination in a warp stop motion: detector bars; a detector bar support having spaced slots each for and seating a respective end of an individual detector bar; a cap structure including a cap base, a cap, and quick-disconnect means attaching the cap to the cap base, the cap including a series of articulated pressure units one for each space between next adjacent detector bar ends and said units being capable when in normal position of exerting downward seating pressure on said detector bar ends; structure holding said detector bar support and said cap base in fixed relative positions with said quick-disconnect means acting to cause said pressure units to occupy said normal position; and means supporting said detector bars at their other ends.

5. In combination in an electric warp stop motion: detector bars each having a live and a ground electrode; a detector bar support having spaced slots each for and seating a respective end of an individual detector bar; a cap structure including a cap base, a cap, and quick-disconnect means attaching the cap to the cap base, the cap including a series of articulated electrically con-

ductive pressure units and means insulating said units from the remainder of the cap structure and there being one of said units for each space between next adjacent detector bar ends and said units being normally self-interconnected electrically and capable when in normal position of exerting downward seating pressure on said detector bar ends and of electrically interconnecting said live electrodes; structure holding said detector bar support and said cap base in fixed relative positions with said quick-disconnect means acting to cause said pressure units to occupy said normal position; and means supporting said detector bars at their other ends.

6. In combination in a warp stop motion of the type having spaced banks of drop wires: spaced detector bars, one for each bank of drop wires; separator bars, one for each space between next adjacent detector bars; means including a base supporting an adjacent end of each separator bar and having upwardly opening slots therein each receiving a respective separator bar end; a detector bar support positioned above said base and having upwardly extending channels each for upward passage of a respective separator bar end therethrough, said support also having horizontally extending spaced slots each for and seating a respective end of an individual detector bar; a cap structure including a cap base, a cap, and quick-disconnect means attaching the cap to the cap base, said cap including a series of articulated pressure units one for each space between next adjacent detector bar ends and said units being capable when in normal position of exerting downward seating pressure on said detector bar ends; structure holding said first named means, said detector bar support and said cap base relatively fixed in said respective positions with said quick-disconnect means acting to cause said pressure units to occupy said normal position; and means supporting said separator bars and detector bars at their other ends.

7. In combination in an electric warp stop motion of the type having spaced banks of drop wires: spaced detector bars, one for each bank of drop wires and each including a live and a ground electrode; separator bars, one for each space between next adjacent detector bars; means including a base supporting an adjacent end of each separator bar and having upwardly opening slots therein each receiving a respective separator bar end; a detector bar support positioned above said base and having upwardly extending channels each for upward passage of a respective separator bar end therethrough, said support also having horizontally extending spaced slots each for and seating a respective end of an individual detector bar; a cap structure including a cap base, a cap, and quick-disconnect means attaching the cap to the cap base, said cap including a series of articulated electrically conductive pressure units and means electrically insulating said units from the remainder of the cap structure, there being one said pressure unit for each space between next adjacent detector bar ends and said units being normally self-interconnected electrically and capable when in normal position of exerting downward seating pressure on said detector bar ends and of electrically interconnecting said live electrodes; structure holding said first named means, said detector bar support and said cap base relatively fixed in said respective positions

with said quick-disconnect means acting to cause said pressure units to occupy said normal position; and means supporting said separator bars and detector bars at their other ends.

5 8. In combination in an electric warp stop motion of the type having spaced banks of drop wires: spaced detector bars, one for each bank of drop wires and each including an upper live electrode a lower ground electrode and insulation separating the two electrodes; separator bars, one for each space between next adjacent detector bars and acting to separate each bank of drop wires from the others; means including a base supporting an adjacent end of each separator bar
10 and having upwardly opening slots therein each receiving a respective separator bar end; a detector bar support positioned above said base and having upwardly extending channels each for upward passage of a respective separator bar end therethrough, said support also having horizontally extending spaced slots each for and seating a respective end of an individual detector bar; a cap structure including a cap base, a cap, and quick-disconnect means attaching the cap to the cap base, said cap including a series of articulated electrically insulating said units from the remainder of the cap structure, there being one said pressure unit for each space between next adjacent detector bar ends and each unit comprising a headed pin mounted on said insulation means, a plate on each pin and retained thereon by the head of the pin, and a spring on the pin tending to press the plate against the head
25 of the pin, said units being normally self-interconnected electrically and capable when in normal position of exerting downward seating pressure on said detector bar ends and of electrically interconnecting said upper live electrodes;
30 structure holding said first named means, said detector bar support, and said cap base in relatively fixed condition in said respective positions with said quick-disconnect means acting to cause said pressure units to occupy said normal position; and demountable means disengageably supporting said separator bars and detector bars at their other ends.

40 9. In a warp stop motion of the type including spaced banks of drop wires and a plurality of detector bars, one for each drop wire bank, supporting and retaining means at each end of said detector bars, and an articulated contact and pressure unit carried by and electrically insulated from one of said supporting and retaining means and quickly removable with a portion thereof, for electrically interconnecting said detector bars and individually pressing each into contact with the supporting means.
